UNITED STATES PATENT OFFICE.

LEWIS G. FRANCIS, OF PASADENA, CALIFORNIA.

PIN-FASTENER.

1,011,937.

Specification of Letters Patent. Patented Dec. 19, 1911.

Application filed February 24, 1911. Serial No. 610,511.

To all whom it may concern:

Be it known that I, LEWIS G. FRANCIS, a citizen of the United States, residing at Pasadena, California, have invented a new and useful Pin-Fastener, of which the following is a specification.

My invention relates to the construction of a simple and effective metallic garter.

The object of the invention is to provide an inexpensive and durable garter that will not loosen accidentally and one which will in no way interfere with the circulation in the leg and which will be comfortable in hot weather. My device also supports the stocking on all sides instead of at one point only. The means by which these beneficial results are attained are set forth in the following specification and shown in the accompanying drawings, in which—

20 Figure 1 is a top plan view of one of my garters open ready for use; Fig. 2 is a side view of the same garter and illustrates the fastening apparatus; Fig. 3 is a fragmental cross section on the dotted line *a—a* in Fig. 2, taken in the direction indicated by the arrow and Fig. 4 is a view of a leg and shows a garter in use.

Throughout the several views like characters refer to like parts.

30 Referring to the details of construction: 1 is a flexible metallic band preferably made round as shown; 2 is an eye or ring formed in the manner shown on one end of said band 1. This eye is bent outward away from the leg at a slight angle to permit the band 1 to enter it in closing. From the eye 2 the guard wire 3 is carried back to a point 4 where it encircles the wire 1 and terminates in the hook 5. 7 refers to the leg of the user's undergarment and 8 refers to the stocking to be supported.

In use the peculiar construction of the ring 2 forms a vital feature. This ring is made large enough to freely admit of the insertion of the wire or band 1. It is set at such an angle to the curvature of the band and fastener that when the point 6 is passed through the eye it will be necessary to spring the point in toward the leg in order to engage it in the hook 5. This produces a binding action between the edges of the ring and the wire or band inserted in it

and when the point is tucked under the hook it is impossible for it to slip out and allow the garter to loosen. It can readily be seen that if the eye or ring were constructed at right angles to the curve of the band no obstacle would be interposed against the loosening of the garter and with too slight an angle it would be difficult or impossible to pass the point through the eye. The exact angle is varied slightly according to the size of the eye and the size of the wire band. But one constructed as shown in the drawings will give satisfactory service. The hook 6 is bent inward toward the leg nearly as far as the guard 3 and the point 6 is held snug against the said guard 3.

In use the garter is opened, the point is passed through the stocking and undergarment, then outside within a short distance. As it is made to encircle the leg this is repeated several times. In Fig. 4 the dotted portion indicates places where the band is inside the sock and undergarment. The point is then passed through the eye 2 and under the hook 6 as above described. In this manner the top of the stocking and undergarment are pinned together at a number of places and the undergarment supports the stocking. The garter may be left as loose as desired when the point is secured in the manner above set forth. The guard prevents the point from injuring the wearer.

The garter may be made of brass, silver, steel or other suitable metal or if desired may be plated with gold or silver. Various lengths may be made and any shape or size of wire used for a band.

Having thus described my invention, what I claim as new and desire to secure by Letters Patent is:

1. In a pin fastener: a curved wire band having one end pointed and having an eye formed at the other end, said eye being bent outward to allow the opposite end of said band to be passed through it; a hook formed on said band adapted to engage the pointed end of said wire; and a guard between the hook and eye adapted to prevent the point from injuring the user.

2. In a pin fastener: a wire band bent to form a circle and having one end pointed; a ring formed on the opposite end of said

band and bent slightly outward from the circle and adapted to receive the pointed end of said wire; a shield formed on said band by continuing said wire from the ring to a point on the band removed from said ring where a hook is formed from the end of said wire; said hook adapted to engage and retain the pointed end of said wire, all as described.

LEWIS G. FRANCIS.
